UNITED STATES PATENT OFFICE.

EDWIN E. PRATT, OF CHICAGO, ILLINOIS, ASSIGNOR TO THE A. N. KELLOGG NEWSPAPER COMPANY, OF SAME PLACE.

DEVICE FOR LOCKING REMOVABLE STEREOTYPES.

SPECIFICATION forming part of Letters Patent No. 296,061, dated April 1, 1884.

Application filed August 9, 1883. (No model.)

To all whom it may concern:

Be it known that I, EDWIN E. PRATT, a citizen of the United States, residing in Chicago, in the county of Cook and State of Illinois, have invented a new and useful Improvement in Devices for Locking Removable Stereotypes, of which the following is a specification.

This invention relates to means for locking removable stereotype-plates to their supporting bed-blocks while in the form, and is designed to avoid some of the evils attending the use of the present forms of fastenings.

The invention consists in the combination, with a plate and bed-block having dovetail or equivalent grooves or recesses, of a collapsible locking device, which may be inserted in the block at any point in the groove therein, instead of at the end, in the customary way.

It further consists in the combination, with such a block and plate, of a locking key or device adapted to collapse for insertion in the groove of the block at any point therein, and to automatically spread and adjust itself to the groove after insertion.

It also consists in the novel construction of the locking device itself, as hereinafter more fully set forth.

In the accompanying drawings, which form a part of this specification, and in which similar letters of reference indicate like parts, Figure 1 is a sectional end view of a plate and block locked together by my invention. Fig. 2 is a view of the block, showing the locking device about to be inserted in the holding-groove thereof. Fig. 3 shows the manner of withdrawing the locking device from the groove. Fig. 4 is an end view of the locking device when not in use. Fig. 5 is a bottom view thereof, and Fig. 6 shows one of the pairs of wings of which the locking device is composed detached.

In said drawings, A represents the plate; B, the block. Each is provided with a longitudinal dovetail groove, b, such grooves registering with one another when the parts are placed together. Into these grooves the locking device is inserted, and said locking device is provided with projecting points which en-

gage with the angling or cut under sides of the 50 grooves.

I construct the locking device of two pairs of wings or arms, c' c'' and c' c'', hinged to each other by a wire, d. A spring, e, encircling said wire d, with its ends pressing against each pair of wings, so as to open or spread them apart, may also be employed, if thought desirable. When the parts are to be locked together, the wings of this collapsible fastening are forced into the position shown in Fig. 2, so that one wing of each pair may enter the groove in the plate at any point between the ends thereof—that is to say, by a vertical movement from above the groove. The plate is then positioned and fastened by slipping it 60 over said locking device by an endwise movement in the usual manner. When it is desired to remove the locking device from the groove, it may be done by pressing upon one of the upper wings, as illustrated in Fig. 3, 70 which causes it to spring readily out of the groove.

This device may be used with great advantage in cases where a number of plates are placed upon a single bed-block. It saves oftentimes the removal of some portion of the plates when an intermediate one of the number is to be changed, as by sliding the plates, those below the one to be changed, sufficiently to uncover one of the locking devices, an opening may be made through which the change desired can be made. The fastening may of course be inserted at the end of the groove in the usual way, as well as elsewhere therein.

It will be understood that any form of groove 85 having the locking or undercut peculiarity of the dovetail groove will be the equivalent in connection with the collapsible locking device of the particular form of groove shown. In this category may be classed T, Y, and 90 analogous forms of groove. It is obvious, also, that the device may be first inserted in the same way in the plate, instead of the block, if that is more convenient. The pivotal wire is preferably provided with an eye, f, at one 95 end, whereby it may be drawn along and positioned in the groove by a hook inserted from the bottom of the form without disturbing the

plate held by it. The wings may of course be pivoted centrally instead of at the ends, as shown, and the eye need not be formed upon the pivotal wire.

5. I claim—

1. The combination, with the plate and block, of an independent and detached collapsible fastening, substantially such as shown.

2. The combination, with the plate and block, of an independent and detached collapsible and self-adjusting fastening, substantially as specified.

3. The fastening or locking device herein shown, consisting of the two pairs of wings or

arms, hinged together and operating substantially as specified.

4. The fastening or locking device consisting of the two pairs of wings or arms hinged together, and the spring for automatically spreading the wings, substantially as specified.

5. The collapsible or hinged locking device provided with the eye or handle, substantially as specified.

EDWIN E. PRATT.
